UNITED STATES PATENT OFFICE.

SCHUYLER BRADLEY POST, OF SYRACUSE, NEW YORK, ASSIGNOR TO JEWELL MANUFACTURING COMPANY, OF AUBURN, NEW YORK, A CORPORATION OF NEW YORK.

THERMOSTAT.

No. 862,755.

Specification of Letters Patent.

Patented Aug. 6, 1907.

Application filed March 13, 1907. Serial No. 362,185.

To all whom it may concern:

Be it known that I, SCHUYLER BRADLEY Post, a citizen of the United States, residing at Syracuse, in the county of Onondaga and State of New York, have invented certain new and useful Improvements in Thermostats; and I do hereby declare the following to be a full, clear, and exact description of the invention, such as will enable others skilled in the art to which it appertains to make and use the same.

10 My invention consists in the novel features herein-after described, reference being had to the accompanying drawing which illustrates one form in which I have contemplated embodying my invention and said invention is fully disclosed in the following description and

15 claims.

Referring to said drawing, Figure 1 represents a front elevation of a thermostat embodying my invention. Fig. 2 is a similar view with the casing removed and clock mechanism thrown back. Fig. 3 is a rear view 20 of the clock mechanism and connected parts, and the mechanism connected to the thermostatic element operated by the clock mechanism, for effecting the adjustment of the said element. Fig. 4 is a horizontal section on line 4—4, of Fig. 1, drawn to an enlarged 25 scale, the clock case being shown in elevation. Fig. 5 is an enlarged detail view of the regulating device for the thermostatic element.

My invention relates to thermostats for regulating heating apparatus in buildings, in which the thermostatic element is provided with adjusting mechanism 30 operated by hand so that the controlled heating apparatus may be operated when different and predetermined temperatures are reached in the room in which the thermostat is located, and it consists in combining 35 with such a thermostat, a clock controlled mechanism for operating the adjusting mechanism which is normally operated by hand, at a predetermined time and to a predetermined point, as will hereinafter more fully appear.

40 In the drawings I have shown my invention in connection with one of the ordinary forms of electric thermostat, now on the market, and which is illustrated in such detail as is necessary for a full and complete understanding of my invention.

45 A represents the main frame of a thermostat, having a detachable case A', upon the exterior of which a thermometer a is conveniently arranged, the case being provided with apertures to permit the air of the room in which it is located, to have access to the interior.

50 B represents the thermostatic element which consists in this instance of a compound metallic strip, composed preferably of brass and steel, or other two metals of differing expansive qualities. One end of the strip B is permanently secured to a stud b, carried 55 on a pivoted plate b' secured to the frame A and capa-

ble of being adjusted on its pivot by a cam b² on a cam shaft b³ mounted in the frame A, and provided with a thumb piece b⁴ by which the said shaft and cam may be operated. The cam shaft b³ is also provided with a pointer b⁵ which plays over a scale b⁶, having a scale 60 indicated thereon, referable to the thermometer, and provided with the indicating words "cooler" and "warmer" as shown. The free end of trip B lies between two adjustable contacts C and C' which are insulated from each other and provided with screws c, c' 65 for attaching suitable wires forming part of the circuits controlled by said thermostat.

The specific construction of the thermostat itself forms no part of my present invention.

Let it be supposed that when the pointer b⁵ is in the 70 central position on the scale as shown in Figs. 1 and 2, the thermostat will operate to maintain the temperature of the room, in which it is located, at a medium temperature, say 60° F. Then if the cam shaft is turned to the left, a lower temperature will be maintained and if turned to the right a higher temperature 75 is maintained.

In using a thermostat of the character just described, it is customary especially where it is located in or adjacent to a sleeping apartment, to turn the regulator 80 shaft b³ to the left at night in order that a lower temperature may be maintained during the night, and to turn the regulator to the right at an early hour in the morning so that the apartment may be warmed quickly. This necessitates the inconvenience of arising and 85 manually operating the regulator in a comparatively cold room, and it is this inconvenience which my invention is chiefly designed to obviate, although the invention may be used for any other purposes for which it may be desirable.

90 In carrying out my invention I attach to the main frame of the thermostat a plate D, which preferably extends below the same and is provided, at one side with the hinge lugs d d and at the other side with a spring catch d'. The shaft b³ of the regulator is provided with an operating arm e, connected by an adjustable link e' to a push rod E mounted in a suitable guide e² on the plate D, and provided at its lower end with a friction roller e³.

95 F represents an ordinary alarm clock of small size, on the back of which is preferably secured a frame, in the form of a ring f, provided with hinge lugs f' f' and a catch lug f². The hinge lugs f' f' are secured to the hinge lugs d d of plate D by a hinge rod f³, thus hinging the clock case to the plate D, and the clock may be 100 rigidly secured in operative position by engaging the catch lug f² with the spring catch d' as shown in Fig. 4.

105 On the back of the clock or its supporting frame f is an oscillating plate or arm G, pivoted at g and connected by a link g' to an arm g², which is connected to 110

the winding stud of the ordinary alarm mechanism of the clock, which stud is provided with the usual winding thumb piece g^3 . Upon the oscillating plate G is pivoted an adjustable trip arm H provided with a trip lug h , which is bent angularly thereto, into position to engage the roller e^3 of the push rod E, as will be clearly understood from the drawings. The trip arm H is adjusted with respect to the oscillating plate G, by means of a screw h' pivotally secured to the trip arm 5 and provided with a nut h^2 , located in a yoke, or slotted plate h^3 , which is pivoted to the oscillating plate G. The trip arm H also carries a pointer h^4 which is bent up over the outer face of the oscillating plate G, and works over a scale on said oscillating plate, the graduations of which exactly correspond with those on the scale b^6 . The clock mechanism is also provided with 10 an additional hand or pointer shown at X, Fig. 1, which may be set to different positions on the dial, so as to trip the alarm mechanism, in the ordinary manner at 15 20 the designated hour.

The normal position of the parts is shown in full lines, Fig. 3, and when it is desired to set the mechanism, the winding thumb piece g^3 is turned so as to move the arm g^2 through 180° (or a half circle) thus winding the 25 spring of the normal alarm mechanism and restoring the tripping arm and oscillating plate to their normal positions. This is necessary and important, as it leaves the mechanism of the thermostat free to be adjusted by hand, at all times except during the actual operation 30 of the clock operated mechanism when tripped. It will also be seen that when the clock mechanism is tripped at the time for which it is set, the arm g^2 will swing back through 180° , thus forcing the tripping arm H into engagement with the push rod E and operating 35 the cam shaft b^3 , and adjusting the thermostatic element, (all of which is accomplished during the first 90° of movement of the arm g^2), and the parts are then returned to normal position, during the last 90° of the movement of said arm g^2 . It will also be seen that the 40 amount of adjustment given to the regulator is accurately determined by the adjustment of the trip arm H with respect to the oscillating plate G. For example, if it is desired to increase the temperature to 75° at a given hour, as say six o'clock a. m., the hand 45 X having been set for six o'clock, the trip arm H is adjusted by means of the nut to such a position on its scale, as corresponds to the position of the pointer b^5 on the scale b^6 to indicate 75° and the apparatus is set by turning the winding thumb piece g^3 so as to wind its 50 adjusting spring. The operator may then manually set the thermostat regulator, to maintain say 60° during the night and at six o'clock the following morning the alarm spring will be released, the trip arm H will be actuated and the cam shaft will be turned to move the 55 pointer b^5 to a position indicating 75° .

While I have shown an ordinary alarm clock employed with my improved mechanism for reasons of economy, it is obvious that a special clock mechanism may be provided having a special actuating mechanism 60 for the arm g^2 , if desired. I find, however, that the ordinary alarm clock answers the purpose and I ordinarily remove the usual bell and hammer of the alarm apparatus, to prevent the additional noise thereof when the time mechanism operates to set the regulator. 65

In order to wind the clock mechanism and set it, and also to set or wind the alarm mechanism or equivalent devices which actuate the regulator of the thermostat, the spring catch may be pressed outwardly to disengage the catch lug f^2 and the clock frame and clock can 70 be swung outwardly to give access to the winding and setting mechanism which as usual is located at the rear of the clock case.

What I claim and desire to secure by Letters Patent 75 is:—

1. The combination with a thermostat provided with manually operated regulating mechanism, of a time mechanism, actuating devices controlled thereby and adjustable connections between said actuating devices and said regulating mechanism for operating the latter at a predetermined time and to a predetermined extent, substantially as described. 80

2. The combination with a thermostat provided with manually operated regulating mechanism, of a time mechanism, actuating devices controlled thereby and adjustable connections between said actuating devices and said regulating mechanism said connections being constructed to permit the free operation of the regulating mechanism by hand, substantially as described. 85

3. The combination with a thermostat provided with manually operated regulating mechanism, of a time mechanism, actuating devices controlled thereby and connections between said actuating devices and said regulating mechanism, said connections being constructed to permit the free operation of the regulating mechanism by hand at 90 all times, substantially as described. 95

4. The combination with a thermostat provided with manually operated regulating mechanism, of a time mechanism, actuating devices controlled thereby and connections between said actuating devices and said regulating mechanism, said connections being normally separated at one point, to permit the regulating mechanism to be adjusted by hand at all times, substantially as described. 100

5. The combination with a thermostat provided with a manually operated regulating mechanism, of a time mechanism, an actuating mechanism controlled thereby, a part operatively connected with said actuating mechanism, a trip arm adjustably connected with said part, and devices connected with said regulating mechanism, having a part normally out of engagement with said trip arm, but located 105 in the path thereof, substantially as described. 110

6. The combination with a thermostat provided with a manually operated regulating mechanism, of a time mechanism, an actuating mechanism controlled thereby, a trip arm connected with said actuating mechanism, lying normally out of operative position, and constructed to be moved into and out of operative position, by a single operation of said actuating mechanism, and devices connected with the regulating mechanism having a part normally out of engagement with said trip arm, but located in the path 115 thereof, substantially as described. 120

7. The combination with a thermostat provided with a manually operated regulating mechanism, of a time mechanism, an actuating mechanism controlled thereby, an oscillating device operatively connected to said actuating mechanism, a trip arm movably connected to said oscillating part, and lying normally in inoperative position, the connection between said oscillating part and said actuating mechanism being constructed to move said trip arm into and out of operative position at a single actuation, an adjusting device carried by said oscillating part, for adjusting the trip arm with respect thereto, to correspond with the desired and predetermined adjustment of the regulating mechanism, and devices connected with said regulating mechanism, having a part normally out of engagement 125 with said trip arm, but located in the path thereof, substantially as described. 130

8. The combination with a thermostat having an adjustable thermostatic element, and hand operated devices for regulating the same, of a clock mechanism, an actuating spring controlled by said clock mechanism, an oscillating plate connected with said actuating spring, an adjustable 140 plate

trip arm connected with said plate, a push rod, having a part normally out of engagement with said trip arm but located in the path of the same, and connections between said push rod and the said regulating mechanism, substantially as described.

9. The combination with a thermostat having an adjustable thermostatic element, and a hand operated regulating device therefor, of a clock casing hinged to the thermostat frame, at one side, a locking device for holding said clock casing in operative position, but permitting it to be swung on its hinge connection to effect the winding and setting of the clock mechanism and the mechanism controlled thereby, an actuating spring controlled by said clock mechanism, an oscillating part pivoted to said clock casing, and opera-

tively connected to said actuating spring, a trip arm adjustably mounted on said oscillating part, a push rod, mounted in a guide secured permanently to the thermostat frame, and having a part normally out of engagement with the trip arm, but located in the path thereof and connections between said push arm and the said regulating mechanism, substantially as described. 15

In testimony whereof I affix my signature, in the presence of two witnesses.
